LLC(57) **CLAIM**

The ornamental design for a colorimeter, as shown and described.

DESCRIPTION

FIG. 1 is a perspective view of the ornamental design for a colorimeter.

FIG. 2 is a front view thereof.

FIG. 3 is a back (or rear) view thereof.

FIG. 4 is a left side view thereof.

FIG. 5 is a right side view thereof.

FIG. 6 is a top view thereof; and,

FIG. 7 is a bottom view thereof.

The portion of the colorimeter shown in broken lines forms no part of the claimed design.
